UNITED STATES PATENT OFFICE

CARL G. OLSON, OF CHICAGO, ILLINOIS, ASSIGNOR TO SHAKEPROOF LOCK WASHER COMPANY, OF CHICAGO, ILLINOIS, A CORPORATION OF DELAWARE

LOCK WASHER

Application filed March 25, 1931. Serial No. 525,093.

My invention relates generally to lock washers and more particularly to lock washers of the type formed with prongs along the margin thereof.

5 It is one of the primary objects of my invention to provide a lock washer of the pronged type, which is adapted to secure nuts and the like against retrograde movement in a very effective manner.

10 More specifically, my invention contemplates the production of a washer, in which the prongs thereof are equipped with sharp work engaging edges adapted to readily embed themselves within a work piece when 15 clamped thereagainst, and to this end I propose to provide prongs of such a cross-sectional shape that acute work engaging edges will be positioned out of the plane of the washer body to lockingly engage the work 20 piece.

Still more specifically, it is an object of my invention to provide a lock washer, as above set forth, having prongs of substantially diamond-shaped cross-section, where- 25 by to present relatively sharp working engaging edges when said prongs are warped out of the plane of the washer body.

Another object of my invention is to provide a lock washer having prongs which are 30 so shaped and warped out of the plane of the washer body that each prong provides oppositely disposed acute work engaging edges which lie in planes spaced from and substantially parallel with the plane of the 35 washer stock.

A still further object is to provide a washer which is shaped and warped as above set forth so that the inclination of successive diagonals will increase from the root to the 40 outer end of the prong, whereby to present increased strutting action at the outer end of said prong.

Still another object of my invention is the provision of a washer formed from flat 45 spring stock having a plurality of spaced marginal prongs, each of said prongs being tapered and having oppositely disposed acute work engaging edges, said edges being deflected out of the plane of the washer stock, 50 so that the inclination of the diagonal at the

outer end of the prong extending between said work engaging edges with respect to the plane of the washer body is greater than the inclination of the diagonal at the root of said prong.

The foregoing and numerous other objects and advantages will be more apparent from the following detailed description when considered in connection with the accompanying drawing, wherein—

55 Figure 1 is a plan view of a washer having external prongs constructed in accordance with the teachings of my invention;

Figure 2 is a side elevational view of the washer of Figure 1;

60 Figure 3 is an enlarged perspective view of one of the prongs of the washer shown in Figures 1 and 2;

Figure 4 is a fragmentary view of a washer having internal prongs constructed similarly to the prongs shown in Figures 1 to 3 65 inclusive;

70 Figure 5 is a semi-diagrammatic end view of a prong, said view taken substantially along the line 5—5 of Figure 1 to more clearly illustrate the manner in which the prong is progressively warped or twisted out of the plane of the washer body;

75 Figure 6 is a semi-diagrammatic view similar to Figure 5 illustrating the manner in which the progressively warped or twisted teeth lockingly engage the work; and.

Figure 7 is an end view of one of the prongs prior to the warping thereof.

80 Referring now to the drawing more in detail wherein like numerals have been employed to designate similar parts throughout the various figures, it will be seen that the disclosed embodiment of my invention includes an annular washer body 10 stamped or otherwise formed from flat spring stock. The body 10 has a plurality of substantially radial prongs 12 spaced along one of the margins thereof. In Figures 1, 2, and 3 I have shown said prongs formed along the external margin, while in Figure 4 I have shown the same along the internal margin of the body. It will be seen that each of the prongs 12 is of tapered form and is warped or twisted out of the plane of the body 10 so 85

as to present work engaging edges 14. These edges 14 are positioned in planes spaced from and substantially parallel with the plane of the body 10, and are adapted to imbed themselves within a work piece, as clearly shown in Figure 6.

Particular attention is directed to the fact that the prongs 12 have a diamond-shaped cross-section, so that the angle A, Figure 5, included between converging sides of each prong is an acute angle. In fact, this acute angle A may be formed previous to the warping of the prongs, as clearly shown in Figure 7, wherein I have disclosed an enlarged end view of a prong before it is subjected to a progressive warp or twist so as to position the work engaging edges 14 out of the plane of the washer body. By having this acute angularity, a very sharp work engaging edge is provided which serves to materially increase the locking effectiveness of the prong when a work piece is clamped thereagainst.

It will also be seen that the prongs 12 are progressively warped or twisted out of the plane of the washer body from the root to the outer end of the prong, so that the strutting action of the outer end of the prong when clamped within the work is materially increased. This will be readily apparent from Figures 5 and 6, wherein I have disclosed for purposes of illustration a plurality of successive parallelograms which represent the cross-sectional shape of the prong taken at various points from the root to the outer end thereof. The inclination of the diagonal at the outer end of the prong with respect to the washer body, as shown by the dot-and-dash lines in Figures 5 and 6, is greater than the inclination of the diagonal extending across the corners at the root of said prong. In other words, my invention contemplates the provision of a washer prong having oppositely disposed acute work engaging edges in which the angularity of the diagonals extending across said prong with respect to the plane of the washer body progressively increases from the root to the outer end of the prong. This arrangement is somewhat similar to the progressive warping disclosed in my Patent 1,782,387, but my present invention provides a material increase in locking effectiveness by having the prong of diamond-shaped cross-section.

In Figure 6 I have shown the effect of a clamping force exerted against the edges 14, and it will be seen that by having the increased strutting action at the outer end of the prong, said prong is capable of withstanding increased clamping forces without becoming flattened. It should also be noted that the edges 14 are deflected out of the plane of the washer body a distance which is less than the thickness of the washer stock so as to provide increased rigidity and strength.

Washers of my improved diamond-shaped cross-section may be made by practicing the method disclosed in my co-pending application, Serial No. 524,453, filed of even date herewith. By practicing this method, the prongs may be initially formed as shown in Figure 7, and subsequently warped out of the plane of the body portion. It should be understood that in using the terms "warped", "twisted", and the like, I do not wish to limit myself to the particular helically twisted arrangement shown in the drawing, but contemplate any prong construction, in which the work engaging edges are acutely formed, and the prong or any portion thereof is warped so as to present these acute edges in substantial parallelism out of the plane of the washer body. My improved washer need not be stamped from flat stock, but may be formed in other ways, as for example, from serrated strip stock.

Obviously the invention is not limited to the specific shape and disposition of the prongs shown in the drawing, but is capable of other modifications and changes without departing from the spirit and scope of the appended claims. For the purpose of more clearly disclosing the structural features of my improved prong construction, I have somewhat exaggerated the acuteness of the work engaging edges. That is to say, the acuteness of the angles A has been slightly exaggerated.

Having thus described my invention, what I claim as new and desire to secure by Letters Patent is:

1. A lock washer formed from flat spring stock including an annular body portion, and a plurality of prongs positioned along and extending from at least one of the margins thereof, said prongs having oppositely disposed acute work engaging edges positioned in planes spaced from and substantially parallel with the plane of the washer body and also having oppositely disposed obtuse edges.

2. A lock washer of flat spring stock having a body portion, and a plurality of locking prongs extending therefrom, the root of each prong being wider than the opposite end thereof, said prongs being warped out of the plane of the washer stock so as to present a plurality of oppositely disposed acute work engaging edges on opposite sides of the plane of the washer body, the diagonal extending between the opposite outwardly projecting corners at the root of each prong being disposed at a less angle to the plane of the washer body than the diagonal extending between the corners at the opposite end thereof, whereby to increase the strutting effectiveness of said opposite end.

3. A lock washer of flat spring stock having a body portion, and a plurality of locking prongs of diamond-shaped cross-section ex-

tending therefrom, the root of each prong being wider than the opposite end thereof, said prongs being warped out of the plane of the washer stock so as to present a plurality of 5 oppositely disposed acute work engaging edges on opposite sides of the plane of the washer body, the diagonal extending between the opposite outwardly projecting corners at the root of each prong being disposed at a less 10 angle to the plane of the washer body than the diagonal extending between the corners at the opposite end thereof.

In witness whereof, I have hereunto subscribed my name.

15
